UNITED STATES PATENT OFFICE.

FRANCIS M. DAVIS, OF CHICAGO, ILLINOIS.

STORAGE STRUCTURE.

1,303,862.

Specification of Letters Patent. Patented May 20, 1919.

Application filed February 5, 1918. Serial No. 215,564.

To all whom it may concern:

Be it known that I, FRANCIS M. DAVIS, a citizen of the United States, and a resident of Chicago, county of Cook, and State of Illinois, have invented certain new and useful Improvements in Storage Structures, of which the following is a specification.

My invention relates to structures for the storage of divers commodities, such as farm produce and other comestibles, dairy products, volatile oils, such as gasoline and the like, and, in fact, for the storage of any articles for which a cool temperature is desirable.

Among the objects of my invention is the provision of a structure the walls whereof shall be, as nearly as possible, of a unitary, monolithic character, and of such arrangement or design that the temperature within the structure may be reduced to a degree sufficient for cooling the articles stored therein. Another object is the provision of a structure that is adapted for use in cooling the articles stored, without employing special refrigeration machinery and the use of ice. It is a further object of my invention to provide a storage structure in which the temperature may be maintained at a relatively low degree and the operation of the same shall be continuous and automatic to a great degree. And other objects are the provision of a structure that is simple in operation, readily assembled and built, and which is novel and useful in its operation.

Other objects and advantages will be obvious to others skilled in this art after an understanding is had from the accompanying drawings which form a part of this specification.

In the drawings,—

Figure 1 is a central vertical section of a storage structure, embodying my invention, portions thereof being broken away.

Fig. 2 is a horizontal, transverse section taken on line 2—2, of Fig. 1.

Fig. 3 is a similar view taken on line 3—3, of Fig. 1.

Referring to the drawings, and more particularly to Fig. 1, it will be observed that a suitable foundation 5 is provided, which is preferably circular in outline, and the area inclosed by this foundation is cemented thickly to provide a floor 6 for the structure. An exterior wall 7, of porous, moisture-absorbing material, is erected, to the top of

which is integrally formed a ceiling 8 that is impervious to water and is disposed horizontally and covers the entire lower structure or storage chamber. The wall 7 is continued up above this ceiling and is made of non-porous material to form the inclosing wall 7^a of a reservoir, basin or tank 9. Within the wall 7 and spaced a distance therefrom, is an inner vertical wall 10, of circular outline, that is spaced away from the outer wall 7 a distance corresponding approximately with the thickness of each wall to provide an inclosed space 11 between the walls, both of said walls 7 and 10 being of a monolithic character. This inner wall 10 is constructed of non-porous, non-absorbing material, and the space 11 between these two walls 7 and 10 is preferably filled with sand or other siliceous material. A suitable roof 12, also of monolithic construction, is fitted upon the top of the tank walls 7^a and is provided with a manhole 13, that is closed by a suitable cover 14, whereby admission may be had to the interior thereof. Suitable openings 16 fitted with caps 15 are provided near the outer rim of ceiling 8, that afford communication between the tank 9 and the space 11 between the upright walls, the purpose of the caps being to seal these openings before the tank is filled with water. A suitable doorway 17 and windows 18, 18 are provided in the walls, for the purpose of access to the interior and to illuminate and ventilate the storage chamber.

A supply pipe 19 extends from a suitable water source up through the floor 6 of the structure, through the central storage chamber 20 and through the ceiling 8 into the tank 9, for the purpose of supplying water to the latter, and a valve 21 controls the flow of the water through said pipe. An outlet draw-off pipe 22 is disposed in the floor 8 of the tank and extends down through the chamber 20 to a suitable outlet 23, and a valve 24 controls the outflow of the fluid to the outlet pipe, while a faucet 25 is provided below said valve for supplying water for divers purposes in the interior of the storage chamber 20. Adjacent the ceiling 8, the outlet pipe 22 is provided with a T 26, into which a valve controlled header 27 is tapped, said header being provided with a plurality of drip or pet-cocks 28, 28, the purpose of which will hereinafter fully appear.

Suitable cross-bars 29 are disposed in horizontal position connecting the inner and outer walls 10 and 7, respectively, in a plane a short distance below the ceiling 8. These 5 cross-bars may be of any convenient design and are preferably disposed radially and suitable distances apart to afford a support for segmental-shaped troughs 30, that are substantially U-shaped in cross-section and 10 are readily assembled in the space 11 through openings 31 made in the upper portions of the inner wall 10. Suitable inverted U-shaped troughs 32, slightly less in width than the troughs 30 and closed at their ends, 15 are disposed in these latter troughs and are each provided with an upwardly projecting hollow stub 33 adjacent their central portion. These stubs 33 have the adjacent ends of 20 pipes 34 terminate in the same and the opposite ends of said pipes 34 are provided with elbows that provide upwardly flared basins 35, disposed below the drip or pet-cocks 28, and the said pipes 34 are supported by suitable straps 34^a depending from the 25 ceiling 8, or in any other suitable manner. These pipes are partially embedded in the wall 10 and partly extend into the doorway 31, so that a suitable block 36 may be fitted into said doorways to close the openings. 30 When the structure is in operation, the reservoir or tank 9 is supplied with a quantity of water and the outlet valve 24 is closed to prevent the escape thereof. The pet-cocks 28 are opened wide enough to permit 35 the water to slowly drip into the basins 35 and through pipes 34 leading therefrom to drip into the segmental troughs 32 through stubs 33. The sand which fills the space 11 between the walls 7 and 10 also 40 covers the troughs and a portion thereof fills in the narrow space between the troughs, but no sand is intended to get under the inverted troughs. The upper edges of the upright troughs 30 are higher than the inverted 45 troughs 32 positioned therein, so that when the water fills the troughs, it will cover the inverted troughs 32 and stand at the level of tops of the troughs 30. The sand or other material of the intermediate wall 11, will, 50 by capillary attraction, cause the water to evenly flow over the top of the outer troughs 30 throughout their length and will evenly moisten or dampen the sand as it trickles down through the same in the space between 55 the walls 7 and 10, and will, to a greater or less extent, compensate for any unevenness in the level of the upper edges of the troughs 30. The inverted troughs 32 will provide an open space in troughs 30, that will be free 60 from sand and when the water drops into the latter troughs, it will at once give an upward pressure to the water in the sand, thereby assisting the capillary attraction thereof to equally distribute a small quantity 65 of water throughout the length of its re-

spective trough 30. The sand wall 11 will also check the too rapid downward flow of the water and will distribute and hold the water against the porous outer wall 7, so that the moisture will be rapidly absorbed thereby. 70 The inner wall being of non-porous material, will repel the water and moisture, so that it will find its only outlet or absorption through the porous wall 7, where, by the action of the atmospheric air, it will become 75 evaporated and the heat for this evaporation will come out of water in wall 7 which, because of the heat conductivity of walls 10 and 11, will absorb the heat from the storage chamber 20, thus causing a constant elimination 80 of the heat from the interior of said chamber.

By means of the sand wall 11 and pet-cocks 28, a greater quantity of water is supplied to the top of wall 7 than to the bottom thereof 85 and there is no forcing of the water through the wall 7, such as would be the case in the event the water were furnished to the wall 7 by a column thereof standing next thereto. In the latter case, the greater supply of 90 water would be furnished at the bottom of wall 7, owing to the pressure of the column, and there would be more water furnished than could well be evaporated, so that it would run off the surface in a liquid form, 95 causing loss of refrigeration, and would also require a greater quantity of water. At any elevation in the sand wall 11, the water contained therein is cooler than the water in any part above it and the water, at any point, 100 contains an accumulation of refrigeration equal to the evaporation from all of the water evaporated from the wall 7 above it. The water that reaches the bottom of the sand wall 11 is the coldest and if it is forced 105 through the porous wall by the water pressure above it, it would be replaced by warmer water coming into it at the top, which would consequently reduce the coefficient of refrigeration. It will be found 110 that when the weather is dry and hot, a temperature can be maintained in the cooling chamber as low as 50 degrees Fahrenheit, although the outside temperature may be 115 100 degrees Fahrenheit. When refrigerated water is desired, the pet-cocks 28 are regulated so that the water will accumulate in the sand wall 11 so as to stand at a level above the faucet 39, which is connected by a pipe 38 to the upper end of a sand point 37 positioned in the sand wall, so that the coldest water can be drawn off through said faucet. 120 It will be noted that the troughs are segmental in shape and independent of each other and also that they are supplied with water from separate pet-cocks. This is essential to the successful operation of a structure of this character for the reason that it will be found that throughout certain sections or areas of the outer surface of wall 7, 125 130

the water will evaporate with greater rapidity than on other sections, as, for example, the side of the wall that receives the action of the sun and the prevailing winds. This construction permits me to regulate the quantity of water supplied to each trough, so that the outer surface of wall 7 may be kept equally moist and a greater amount of water may be absorbed thereby.

10 In the event the structure is to be used for storing volatile oils, such as petroleum or gasolene, the doorway is made in the form of a manhole tightly closed and sealed by an iron door, and the pet-cocks 28 are 15 then regulated through the window in the top, from the exterior of the structure. In this event, the wall 7 is made denser so as to carry a larger head of water in the sand wall and prevent the water running down 20 the exterior thereof. The tank at the top can be made shallow and without a cover, if desired. As is well known, there is a considerable loss in the gasolene qualities of petroleum, caused by evaporation in the 25 storage tanks, due to the heat on the tanks, and in many cases the escaping gas attracts lightning and the tank is fired, causing the destruction of the tank and its contents. When oil is stored in a structure of the kind 30 I have designed, its temperature is lowered by the evaporation of the water on the outside wall and the water in the tank at the top of the structure, thus preventing the oil from being converted into gas by heat, and 35 this gas could not escape from the structure by reason of the inner wall being entirely surrounded by a water seal.

When it is desired to cleanse the sand or remove it, the caps 15 heretofore mentioned 40 are removed from the opening 16 in the ceiling 8, and the water in the tank is permitted to flush down through these openings 16 and out through faucets 40 at the bottom of the outer wall, or, in lieu thereof, if the 45 tank is empty, the supply pipe is opened to flush the same. These faucets 40 are disposed upon the outer side of suitable plugs 41 that are tapped into thimbles 42 secured in the wall and in the event the sand itself 50 is to be removed, these plugs 41 may be unscrewed and the same taken out from these manholes.

While I have illustrated a specific manner 55 of making this structure, the principles thereof may be embodied in other types of structures, without materially departing from the spirit of my invention and I, therefore, desire it understood that I do not limit myself to the precise devices illustrated, 60 as the drawings are, in a sense, merely

diagrammatic for convenience of illustration.

What I claim is:—

1. A storage structure comprising an impervious inner wall and a porous evaporating outer wall spaced apart to provide a space between the same, moisture-carrying material in said space, a plurality of troughs disposed in the upper portion of said space, means for supplying a liquid to said troughs, and devices for controlling the quantity of liquid supplied to each trough. 65 70

2. A storage structure comprising an outer moisture-absorbing wall, an inner non-absorbing wall spaced therefrom, moisture conveying material in the space between said walls, and means for supplying and controlling the quantity of liquid discharged into 75 said moisture-conveying material.

3. A storage structure comprising an outer moisture-absorbing wall, an inner non-absorbing wall spaced therefrom, moisture-carrying material in the space between said walls, separate troughs in the upper portion of said material, a feed pipe leading to each trough, and means for controlling the quantity of liquid supplied to each feed pipe. 80 85

4. A storage structure comprising an inner impervious wall, an outer porous wall spaced therefrom, moisture distributing material between said walls, means for supplying moisture to said material, means for regulating the quantity of moisture so supplied, whereby the moisture utilized in evaporation is made up and no excess of unevaporated moisture cooled by evaporation is permitted to escape. 90 95

5. A storage structure comprising an inner substantially impervious wall, an outer relatively porous wall, an interior storage compartment, a liquid tank above said compartment, and means in said storage compartment for supplying and distributing water to said exterior wall. 100

6. A storage structure comprising inner and outer walls spaced apart the latter wall being porous and capable of evaporating moisture, moisture-distributing material in the space between said walls whereby moisture is conveyed to said outer wall, and means for supplying moisture to said material including a trough embedded in and surrounded by said material. 105 110

Signed at Chicago, county of Cook, and State of Illinois, this 2nd day of February, 115 1918.
